BASS GUITAR

Clarence L. Fender, Fullerton, Calif.

Application January 6, 1959, Serial No. 54,050

Term of patent 14 years

(Cl. D56—1)

I claim:

The ornamental design for a bass guitar, substantially as shown.
